UNITED STATES PATENT OFFICE

HENRY JOSEPH ROUND, OF LONDON, ENGLAND, ASSIGNOR TO RADIO CORPORATION OF AMERICA, A CORPORATION OF DELAWARE

MICROPHONE

Application filed June 21, 1927, Serial No. 200,339, and in Great Britain July 8, 1926.

This invention relates to microphones, and more particularly to microphones of the type known generally as "carbon microphones," in which a change of current, consequent upon a change of resistance of carbon, is effected by the incidence of sound waves.

According to this invention a carbon microphone comprises a layer of carbon powder or the like in contact with a plurality of solid carbon electrodes, for example, carbon disks or rods, arranged transversely (i. e. the positive electrodes and the negative electrodes lie more or less in a line at right angles to the lines of incident sound), the whole arrangement being such that, in the main, change of current is produced in the same direction as the pressure due to the sound waves.

The invention is illustrated in the accompanying drawings, in which Figure 1 is an end elevation partly in section and Figure 2 is a plan view showing the casing 2 in section. Figure 3 is an explanatory diagram showing the main directions of sound pressures and current lines of flow.

Referring to the figures, 1 are electrodes formed of rods of carbon, let into a massive and substantially non-resonant body 2 of wood or other insulating material, or of metal having an insulated surface or cover. The rods preferably lie flush with the insulated surface of the body 2, as shown, and are covered with a layer of carbon powder 3 which is held in place by means of a thin diaphragm 4 of mica or other relatively non-yielding material. Alternate rods are connected together, one set to the positive terminal of the microphone and the other to the negative.

In a modification the rods 1 of carbon are replaced by a plurality of disks whose flat surfaces lie substantially flush with the insulated surface of the body 2. Where disks are employed, a satisfactory arrangement is to provide an equal number of positive and negative disks evenly arranged, for example, over the surface of a square.

It will be seen from Figure 3, (in which the dotted lines represent lines of pressure and the dashed lines represent lines of current) that when sound waves strike a microphone,

as above described, the sound pressure is transmitted to the carbon powder in suchwise that changes of current take place, in the main, in the same direction as that of the sound waves, as distinct from the usual known microphones of the transversely disposed electrode type, in which the current changes occur substantially at right angles to this direction of sound waves.

I have found that good results are obtained if the layer of carbon powder does not exceed 2 mm. in depth and the width or diameter of the rods or disks does not exceed 5 mm.

Having now particularly described and ascertained the nature of my said invention and in what manner the same is to be performed, I declare that what I claim is:

1. In an electro-acoustic device, a plurality of stationary electrodes positioned to form a substantially flat surface, a layer of conducting, powdered material in contact with the flat surface formed by said electrodes, means for applying pressure to said material whereby its conductivity is changed and leads connecting alternate electrodes in parallel.

2. In an electro-acoustic device, a plurality of stationary electrodes mounted in a common plane, a circuit connected to said electrodes, a conducting, pulverulent material covering said electrodes and substantially rigid means adapted to be actuated by a sound wave for applying pressure to said material, said means and said electrodes lying in substantially parallel planes.

3. A microphone comprising at least three stationary electrodes having their surfaces arranged in parallel relation, a non-yielding diaphragm spaced from said surfaces and a mass of granular, conducting material filling the space between said electrodes and said diaphragm.

4. A microphone comprising a body having a plurality of grooves therein, at least three electrodes seated in said grooves, a diaphragm mounted adjacent said electrodes, a mass of conducting material contacting said electrodes and said diaphragm and a lead connecting two of said electrodes in parallel.

5. An electro-acoustic device comprising a plurality of electrodes arranged in parallel

relation, a diaphragm spaced from said electrodes and a mass of conducting material filling the space between said electrodes and said diaphragm, the thickness of said mass being substantially two-fifths the width of
5 said electrodes.

6. An acoustic device comprising a stationary base member provided with at least three grooves formed therein, electrodes conforming to the curvature of said grooves
10 seated therein and having flat tops arranged in a plane, a mass of granular, conducting material covering said electrodes, and a non-yielding diaphragm arranged in contact with said mass and adapted to vary the resistance thereof in accordance with incident sound waves.

HENRY JOSEPH ROUND.
